(57) CLAIM

The ornamental design for a combined outdoor grill and smoker, as shown and described.

DESCRIPTION

FIG. 1 is a top, front and right side perspective view of a combined outdoor grill and smoker showing my new design; FIG. 2 is a top, front and left side perspective view thereof; FIG. 3 is a left side view thereof; FIG. 4 is a right side view thereof; FIG. 5 is a rear view thereof; FIG. 6 is a front view thereof; FIG. 7 is a top view thereof; and, FIG. 8 is a bottom view thereof. The broken lines shown in FIGS. 1 and 2 illustrate the environment of the article and form no part of the claimed design.
